CLAIM

The ornamental design for a product delivery door for vending machine, as shown and described.

DESCRIPTION

FIG. 1 is a front perspective view of a product delivery door for vending machine according to a first embodiment of my new design;

FIG. 2 is a front perspective view showing the product delivery door of FIG. 1 in a partially open position;

FIG. 3 is a front perspective view showing the product delivery door of FIG. 1 in a different partially open position; FIG. 4 is a front perspective view showing the product delivery door of FIG. 1 with the door in a totally open position;

FIG. 5 is a front view of the vending machine of FIG. 1; FIG. 6 is a right side view of the vending machine of FIG. 1;

FIG. 7 is a left side view of the vending machine of FIG. 1; FIG. 8 is a rear view of the vending machine of FIG. 1; FIG. 9 is a top plan view of the vending machine of FIG. 1; FIG. 10 is a bottom plan view of the vending machine of FIG. 1;

FIG. 11 is a front perspective view of a product delivery door for vending machine according to a second embodiment of my new design;

FIG. 12 is a front perspective view showing the product delivery door of FIG. 11 in a partially open position;

FIG. 13 is a front perspective view showing the product delivery door of FIG. 11 in a different partially open position;

FIG. 14 is a front perspective view showing the product delivery door of FIG. 11 with the door in a totally open position;

(Continued)

FIG. 15 is a front view of the vending machine of FIG. 11; FIG. 16 is a right side view of the vending machine of FIG. 11; FIG. 17 is a left side view of the vending machine of FIG. 11; FIG. 18 is a rear view of the vending machine of FIG. 11; FIG. 19 is a top plan view of the vending machine of FIG. 11; FIG. 20 is a bottom plan view of the vending machine of FIG. 11; FIG. 21 is a front perspective view of a product delivery door for vending machine according to a third embodiment of my new design; FIG. 22 is a front perspective view showing the product delivery door of FIG. 21 in a partially open position; FIG. 23 is a front perspective view showing the product delivery door of FIG. 21 in a different partially open position; FIG. 24 is a front perspective view showing the product delivery door of FIG. 21 with the door in a totally open position; FIG. 25 is a front view of the vending machine of FIG. 21; FIG. 26 is a right side view of the vending machine of FIG. 21; FIG. 27 is a left side view of the vending machine of FIG. 21; FIG. 28 is a rear view of the vending machine of FIG. 21; FIG. 29 is a top plan view of the vending machine of FIG. 21; FIG. 30 is a bottom plan view of the vending machine of FIG. 21; FIG. 31 is a front perspective view of a product delivery door for vending machine according to a fourth embodiment of my new design; FIG. 32 is a front perspective view showing the product delivery door of FIG. 31 in a partially open position; FIG. 33 is a front perspective view showing the product delivery door of FIG. 31 in a different partially open position; FIG. 34 is a front perspective view showing the product delivery door of FIG. 31 with the door in a totally open position; FIG. 35 is a front view of the vending machine of FIG. 31; FIG. 36 is a right side view of the vending machine of FIG. 31; FIG. 37 is a left side view of the vending machine of FIG. 31; FIG. 38 is a rear view of the vending machine of FIG. 31; FIG. 39 is a top plan view of the vending machine of FIG. 31; and,

FIG. 40 is a bottom plan view of the vending machine of FIG. 31.

The broken line shown is for the purpose of illustrating portions of the vending machine that forms no part of the claimed design.
